Primary Examiner — Charles D Hanson(74) *Attorney, Agent, or Firm* — Tredecim LLC; Sean L. Sweeney; Taylor A. Noonan(57) **CLAIM**

The ornamental design for a portable storage container, as shown and described.

DESCRIPTION

FIG. 1 is a perspective view of a portable storage container showing my new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

In the drawings, the broken lines depict portions of the article that form no portion of the claimed design.
